See application file for complete search history.

FIG. 1 is a left side view of a first embodiment of a pipette showing my new design;

FIG. 2 is a front side view of the design of FIG. 1;

FIG. 3 is a right side perspective view of the design of FIG. 1;

FIG. 4 is top perspective view of the design of FIG. 1;

FIG. 5 is a left side view of the design of FIG. 1, showing the outer pipette cylinder and internal piston as separate components; and,

FIG. 6 is a top plan view of the design of FIG. 1;

FIG. 7 is a bottom plan view of the design of FIG. 1;

FIG. 8 is left side view of a second embodiment of a pipette showing my new design;

FIG. 9 is a front side view of the design of FIG. 8;

FIG. 10 is a right side perspective view of the design of FIG. 8;

FIG. 11 is a top perspective view of the design of FIG. 8;

FIG. 12 is a left side view of the design of FIG. 8, showing the outer pipette cylinder and internal piston as separate components;

FIG. 13 is a top plan view of the design of FIG. 8; and,

FIG. 14 is a bottom plan view of the design of FIG. 8.
